LASTING MACHINE

Michele Cuozzo, Lynn, Mass.

Application July 31, 1933, Serial No. 682,928

11 Claims. (Cl. 12—7)

This invention relates to the creation of, and improvements in, a lasting machine in which a pair of side wipers and a wiping wire mechanism together with coordinating parts and controlling mechanism, function as lasting means.

The objects of the invention are to render possible the lasting of a shoe on a single machine; to provide a lasting machine of greater size range than has heretofore been available; to provide a lasting machine requiring a minimum of shoe handling; to speed up production; to minimize production costs; to afford perfection in lasting; and to provide the various other advantages and results made evident from the following specification.

The machine embodies a toe portion wire wiping mechanism and a pair of side wipers which function to last a shoe at the shank and heel portions, and hold the shoe in place upon the jack while the wire wiper functions at the sole and toe portions of the shoe, together with operating means.

I attain the objects of the invention as shown in the accompanying drawings which form a part of this specification and in which similar letters of reference refer to similar parts throughout the various views. The shoe is first prepared for the lasting operation by assembling the upper and insole upon a last and applying to the exposed portion of the insole and the adjacent portions of the upper a suitable coating of cement or other suitable adhesive which is allowed to dry. The last with the upper thereon is then placed upon the jack of the machine, hereinafter more particularly described.

It will be understood that said assembling includes the temporary placing of sufficient lasting tacks to hold the shoe upper as assembled.

In the drawings, Figure 1 is a partial plan view looking down upon the machine, with the side wipers and wire wiping mechanism in open position, and an assembled shoe in position upon the jack ready to be lasted. Figure 2 is a sectional side view taken on line 2—2 in Figure 1 except that the side wipers are shown clamped onto the shoe in a closed position and the mechanism which operates the side wipers is but partially shown. Figure 3 is a sectional view taken on line 3—3 in Figure 2, and shows the side wipers in closed position. Figure 4 shows a sectional view similar to Figure 3 except that the side wipers are in an open position. Figure 5 is an enlarged plan view of one of the wire wiping mechanisms. Figure 6 is a side view of the mechanism shown in Figure 5. Figure 7 is a

sectional view on line 7—7 in Figure 1, showing the guiding and swinging construction of the wire wiper arms. Figure 8 is a plan view showing the side wipers in partially closed position with the wiper wire in contact with the toe of the shoe, a part of the upper being lapped over the wire and held in such lapped position by means of a clamp. Figure 9 simulates Figure 8 with the wire wiper in closed position about the sole. Figure 10 is a fragmentary longitudinal sectional view taken through the forward part of the last as shown in Figure 9 showing the operation of the clamp which holds in lapped position the lapped portion of the upper with the wire therebetween.

Referring again to the drawings, A shows the frame upon which the machine is built. B¹ and B² show side wipers mounted upon and operated by the cam arms D¹ and D², which are held in operating position and slide between the guides C¹, C², C³ and C⁴. The cam rolls E¹ and E² are mounted upon the guides C¹, C², C³, and C⁴ by the studs E³ and E⁴. The springs F¹ and F² hold the cam arms D¹ and D² against the cam rolls E¹ and E² and tend to maintain the side wipers in open position as shown in Figure 4. When downward pressure is applied to the connection H (by means of a foot treadle or a power operated mechanism) the cam pivoting block G secured thereto moves downward, whereupon the cam arms D¹ and D² secured to the block G at G¹ and G², operate against the cam rolls E¹ and E² and move the side wipers B¹ and B² to closed position.

A shoe J is shown on a last I which in turn is mounted upon the jack K. The jack is adjustable by means of the adjusting sleeve L and the spring M so as to allow the last to yield under pressure. The rod N and the nuts O and O¹ function to adjust the tension of the spring M. The toe of the shoe is supported by a yielding pad P, adjustable by means of an adjusting sleeve Q, and the spring R so as to allow the pad P to yield under pressure; the tension of the spring R is adjustable by means of the rod S, and the nuts T and T¹. The back rest U pivots upon the pin U¹ on the frame A and is adjustable to any desired position by means of the set screw U². The back rest is designed to avoid slipping of the shoe when the side wipers are not used or when otherwise required.

The wiper mechanism comprises preferably a strong spring tempered wire V (but any suitable wire or other substance capable of standing the strain may be used) maintained under tension by means of two springs V¹ and V² over and

around the toothed rolls V^3 and V^4 which in conjunction with the wire help to wipe the fore-part of the shoe and which are mounted on and revolve on the studs V^6 and V^7 , between the wire 5 wiper arms W^1 , W^2 , W^3 , and W^4 , which are in pairs and slide in the swinging brackets W^8 and W^9 held in position by means of the spring W^5 . As the arms advance into the so called closed position, the toothed rolls V^3 and V^4 following 10 the shape of the sole of the shoe, cause the arms W^1 , W^2 , W^3 , and W^4 to open and allow the toe of the shoe to pass therebetween as shown in Figure 9. The rolls W^6 and W^7 fit into and slide in the slots Y^1 and Y^2 in the sliding bracket Y , 15 and allow the arms W^1 and W^3 to move into a relatively parallel position as the bracket Y is pulled forward by means of the flexible connection Y^3 , passing over the roll Y^8 pivoted on the stud Y^9 on the frame A , and operated by a 20 foot treadle or power mechanism. The tension of the spring Y^4 , secured to the pin Y^6 in the frame A and the pin Y^5 on the slide Y , brings the sliding bracket Y backward to its original position when the pressure is released on the 25 flexible connection Y^3 . As the sliding bracket Y travels forward, the wire of the wiper arms mounted thereon likewise moves forward to function together with the help of the toothed rolls in the wiping and complete lasting of the 30 toe and forward portion of the shoe.

Only one arm is shown in Figures 5 and 6, but it will be understood that both arms are of similar construction. The rolls V^3 and V^4 are likewise identical for which reason V^4 only is 35 shown. The rolls V^3 and V^4 are grooved at V^8 to afford a proper guide for the wiping wire, and are flanged and toothed at V^5 to provide means for forcing the upper over the sole as the wiper wire moves forward. As the wiper wire is brought 40 onto the toe, a portion of the upper Z (see Figure 10) is lapped over the wire V and held in lapped position by the clamp X , mounted on the frame A by the pin X^1 , and is held in clamping position by a spring X^2 . After the portion Z 45 of the upper is lapped at the toe and secured in lapped position by the clamp X , the wiper wire is moved into closed position as shown in Figure 9, and together with the toothed rolls as described completes the lasting operation at the 50 fore portion of the shoe.

The spring V^2 is adjustably mounted by fastening the spring to an eye bolt V^{11} with the nut V^{12} . Tension is supplied by loosening or tightening the nut V^{12} (see Figures 5 and 6).

55 While I have illustrated and described a preferred construction for carrying my invention into effect, this is capable of variation or modification without departing from the spirit of the invention. I therefore do not wish to be limited 60 to the exact details of construction herein set forth, but desire to avail myself of such variations and modifications as come within the scope of the appended claims.

Having thus described my invention, I claim 65 as new and desire to secure by Letters Patent of the United States of America:—

1. A shoe lasting machine comprising a frame, a jack thereon to receive a last, a support on the frame, a wiper wire on the support, means 70 for clamping the wire to the toe portion of an upper on the last, and means for moving the support and thus the wire relative to the last to cause the wire to wipe the unclamped portion of the upper onto the last.

75 2. A device as claimed in claim 1, wherein

resilient means are provided for holding the wiper wire taut on the support.

3. A device as claimed in claim 1, wherein the wiper wire support comprises a pair of pivotally and slidably mounted wire supporting arms. 80

4. A shoe lasting machine comprising a frame, a jack thereon, a support on the frame, a pair of rolls on the support, a wiper wire on the support and trained around the rolls, said rolls having flanges thereon, means for clamping the forward part of an upper on the last thereto, means for moving the support over the last to cause said flanges to turn the upper on the last over the sole in advance of the wiper wire during movement of the support over the last. 85

5. A lasting machine comprising a frame, a jack mounted thereon to receive a last, means for supporting the last, a wire wiper mechanism comprising a plurality of rolls, said wire running on the rolls, movably mounted on the frame, said wire being adapted to wipe the forward portion of the upper of a shoe on the last when placed on said jack, means for wiping the rear portions of said upper, and means operating said machine in the performance of its wiping and lasting operation. 95

6. A shoe lasting machine comprising a frame, a jack thereon to receive a last, a support slideable on the frame, wiper wire supporting arms pivotally and slidably mounted on the support, 100 rolls on the arms, a wiper wire loop having its terminals yieldably connected with the arms, said wire being trained around the rolls, and means for moving the support over the last to cause the wiper wire to wipe the upper of a shoe on the 110 last.

7. A shoe lasting machine comprising a frame, a jack on the frame to receive a last, a wiper wire mechanism slideable on the frame, rolls on the mechanism, said rolls having flanges thereon, 115 a wiper wire of the mechanism being trained around the rolls, and means for advancing the mechanism toward the last to cause the flanges to wipe the forward portion of an upper on the last in advance of the wiping thereof by the 120 wiper wire.

8. In a machine adaptable for lasting shoes, a frame, a jack mounted thereon adaptable to receive a last, means for adjustably cushioning said last upon said jack, together with other adjustable cushioning means supporting said last, a wiper wire mechanism, comprising a wire and a plurality of grooved toothed rolls, said wire running in the grooves on said rolls, movably mounted on said frame adaptable to wipe the 125 forward portion of the upper of a shoe on a last when placed on said jack, means for wiping the rear portions of said upper, and means for operating said machine in the performance of its 130 wiping and lasting operation.

9. In a machine adaptable for lasting shoes, a frame, a jack mounted thereon adaptable to receive a last, means for adjustably cushioning said last upon said jack, together with other adjustable cushioning means supporting said last, a wiper wire mechanism, comprising a wire and a plurality of grooved toothed rolls, said wire running in the grooves on said rolls, movably mounted on said frame adaptable to wipe the 135 forward portion of the upper of a shoe on a last when placed on said jack, means for holding the wire wiper in position at the toe of said shoe, means for wiping the rear portions of said upper, and means for operating said ma-

chine in the performance of its wiping and lasting operation.

10. In a machine adaptable for lasting shoes, a frame, a jack mounted thereon adaptable to receive a last, means for adjustably cushioning said last upon said jack, together with other adjustable cushioning means supporting said last, a wiper wire mechanism, comprising a wire and a plurality of grooved toothed rolls, said wire running in the grooves on said rolls, movably mounted on said frame adaptable to wipe the forward portion of the upper of a shoe on a last when placed on said jack, means to insure the fixed position of a shoe upon the last, means 15 for wiping the rear portions of said upper, and

means for operating said machine in the performance of its wiping and lasting operations.

11. In a machine adaptable for lasting shoes, a frame, a jack mounted thereon adaptable to receive a last, means for adjustably cushioning said last upon said jack, together with other adjustable cushioning means supporting said last, a wiper wire mechanism, comprising a wire and a plurality of grooved toothed rolls, said wire running in the grooves on said rolls, movably mounted on said frame adaptable to wipe the forward portion of the upper of a shoe on a last when placed on said jack, and means for operating same.
